UNITED STATES PATENT OFFICE.

WILLIAM H. HULTGREN, OF PHILADELPHIA, PENNSYLVANIA, ASSIGNOR TO OTIS ELEVATOR COMPANY, OF JERSEY CITY, NEW JERSEY, A CORPORATION OF NEW JERSEY.

COMBINED BRAKE APPARATUS AND SWITCH MECHANISM.

979,498.

Specification of Letters Patent. Patented Dec. 27, 1910.

Application filed June 21, 1907. Serial No. 380,037.

To all whom it may concern:

Be it known that I, WILLIAM H. HULTGREN, a citizen of the United States, residing at Philadelphia, in the county of Philadelphia and State of Pennsylvania, have invented a new and useful Improvement in Combined Brake Apparatus and Switch Mechanism, of which the following is a specification.

10 My invention relates to hoisting apparatus and one of its objects is the provision of improved and efficient means for controlling the operation of such apparatus.

More particularly it is the object of my 15 invention to provide the shipper sheave of an elevator with simple and efficient means for effecting the operation of brake mechanism and the operation of motor-controlling means of a direct-current electric 20 motor.

Other objects of the invention will appear hereinafter, the novel combinations of elements being pointed out in the claims.

In the accompanying drawings, Figure 1 25 is a front elevation of my invention and Fig. 2 is a side elevation of the same; Fig. 3 illustrates diagrammatically the circuits and connections; and Figs. 4, 5 and 6 are modifications of the reversing switch; Fig. 30 7 is a view similar to Fig. 1 of a modification; Fig. 8 is a side elevation of Fig. 7, and Figs. 9 and 9^a show in front and side elevation a traveling nut forming part of the stop-motion device.

35 Referring to Figs. 1 and 2, the reference number 13 designates the housing of a worm wheel and 14 the worm casing of a well-known type of hoisting apparatus. 15 designates the worm shaft to which is fixed the 40 brake pulley 16. The brake comprises the bands 18 and 19 which are secured at their lower ends to the bracket 20 which is an extension of the oil drip 21 secured at 22 to the right-hand end of the worm casing 14. 45 The upper ends of the brake bands 18 and 19 are connected at the points 23, 24 to the lever 25 pivoted at 26 to an extension of the housing 13. The lever 25 forms part of the 50 brake-applying means which comprises a link 27, connected at its lower end to the lever 25, and a cam-operated lever 28 to which the upper end of the link 27 is connected. The lever 28 is pivoted to a rod 29, connected at its inner end to the housing 13. The inner end of the lever 28 has

a flat cam engaging surface 30, extending horizontally beneath a cam 31. The cam 31 is rigidly connected to rectangular frame 32 to which in turn is connected the shipper sheave 33. When the sheave 33 is in its 60 central or normal position as shown in Fig. 1, the cam 31 is out of engagement with the contact surface 30, and the brake is applied. The brake may be held in this position by a weight 99 secured to the end of the lever 25. 65 When the shipper sheave is moved in either direction, the cam 31 engages the cam surface 30 and moves the lever 28 about its fulcrum. This operates through the link 27 to lift the inner end of the lever 25, and re- 70 move the brake bands 23 and 24 from the brake wheel.

A slack cable device is provided which comprises a lever 35 pivoted to an arm 36 which is secured to the housing 13. The 75 inner end of the arm 35 has pivoted to it a link 37, which is connected at its upper end to a horizontal arm 38 on the rock shaft 39. Carried by the rock shaft 39 are two vertical rock-arms 40 and 41 which straddle the 80 shaft 17 and have lugs at their upper ends engaging between the flanges 42 of a slideable clutch member 43 feathered on the shaft 17. The clutch member 43 is adapted to be moved into engagement with a clutch 85 member 44 connected to move with the shipper sheave. The lever 35 is held in a horizontal position as shown in Fig. 2 by the tension of the cable in any well known manner. When any slack in the cable occurs, 90 the outer end of the lever 35, which may be weighted, will be moved downwardly. This movement of the lever will operate through the link 37 to swing the rock shaft 39 and move the clutch member 43 into 95 engagement with the member 44. This will connect the shipper sheave for rotation with the shaft 17, and operate to permit the application of the brake and operate the motor-controlling switches in a manner hereinafter 100 fully described.

The stop motion device is shown most clearly in Fig. 8. As here shown a portion of the shaft 17 is somewhat reduced in diameter and screw threaded. Adjustably secured to the threaded portion of the shaft for rotation therewith are the stops 45 and 46 between which is the traveling nut 47 shown in detail in Figs. 9 and 9^a. The nut 47 is held against rotation independently of 105

the shipper sheave by a shoulder or projection 48 carried by the shipper sheave engaging a recess or groove 49 in one side of the nut 47. The nut 47 travels longitudinally of the shaft 17 as the shaft rotates, the shipper sheave being prevented from moving longitudinally; and as the elevator car reaches its limit of travel in either direction, the traveling nut engages one of the stops 45, 46, and is rotated thereby, carrying the shipper sheave with it, and stopping the elevator in a well-known manner. The traveling nut 47 also has an arm 88 extending from one side and guided between lugs 89 (Fig. 7) on the shipper sheave. The arm 88 extends underneath the contact surface 30' of a lever 28' forming part of a modified form of brake-operating device. The lever 28' is fulcrumed at 29' in a frame 29" secured to the housing 13. The outer end of the lever 28' is connected by a link 27' to the end of a lever 25' similar to the lever 25 in Fig. 1, and having the brake bands secured thereto in the same manner. The lever 25' has an extension 90 to which is secured a weight 91 which tends to swing the lever 25' to release the brake bands. When the shipper sheave is in its normal position as shown in Fig. 7 the arm 88 on the traveling nut 47 holds the lever 28' in a position to apply the brake against the action of the weight 91. When the shipper sheave is moved in either direction, the arm 88 is carried out of contact with the lever 28', allowing the weight 91 to operate the lever 25' and release the brake.

Secured to the shipper sheave is a pendulum arm 92 to which is adjustably secured a weight 93. If the sheave is moved in a clockwise direction this weighted arm 92 will be moved upwardly and past a vertical position, and tend to hold the sheave in position with the switch contacts in engagement with each other as hereafter described. If the sheave is moved in a counterclockwise direction, the weighted arm will be moved downwardly, but not far enough to carry it past the center to the right hand side. The weight will therefore operate to firmly hold the switch closed against accidental displacement when the shipper sheave has been moved in either direction. The range of movement of the shipper sheave is limited in each direction by stops 95, 96 on the sheave engaging fixed stops 97, 98, respectively.

The electrical circuits for the motor are automatically controlled by switches associated with the shipper sheave or flier and operated thereby. These switches will now be described. Secured to the casing 14, (Fig. 2) is a bracket 50, to which is bolted a U-shaped frame 51. To the frame 51 are secured insulating plates 52, 52' which support respectively the fixed contacts 53, 54,

55, 82, 72, 83 and 53', 54', 55', 79, 80, 81 of the switches. Carried by the shipper sheave are two pairs of knife blades 56, 56' and 57, 57' arranged to engage with the fixed contacts or clips when the sheave is oscillated in either direction. The blade 56 is arranged to electrically connect the contacts 53, 54, 55, the blade 56', the contacts 82, 72, 83 and so on. The knife blades are pivoted at 58, and are normally held in a vertical parallel position against an intermediate block 59, by a coil spring 60 uniting the upper ends of the knife blades. This arrangement insures a snap action or quick opening of the switch. If a knife blade 56 is moved into engagement with the contacts 53, 54, 55, and the sheave is then moved in the opposite direction, the knife blade 56 will be held in position by frictional engagement with the clip contacts 53, 54, 55 and will swing on its pivot 58 as the sheave commences to move back. The blade 56', however, will be prevented by the block 59 from swinging with the blade 56. The ends of the blades are therefore separated until the tension of the spring 60 overcomes the friction between the blade 56 and the clips, and the blade is snapped out, breaking the circuit quickly and reducing the arc following.

Fig. 3 shows diagrammatically the switches, and motor and controlling circuits. The motor M which is adapted for use with a direct current, has a shunt field winding F, and a series winding G. An accelerating magnet H controls the series winding G and the accelerating resistance R. The main or armature circuits are represented by heavy lines, and the shunt circuits by light lines. The switch blades 56 and 57 are insulated from each other, but move together about the pivot 60, corresponding to the pivot for the shipper sheave. When these blades are moved in a counterclockwise direction the blade 56 will engage with the contacts 53, 54 and 55 electrically uniting them. The blade 57 will at the same time bridge the contacts 53', 54' and 55'. This closes a circuit through the motor as follows:—from the positive main by wire 61 to and through contact 55', blade 57, contact 53', wire 63, brush 64, the armature, brush 65, wire 66, contact 55, blade 56, contact 53, wire 67, accelerating resistance R, wire 68, series winding G to the negative main. A circuit is also closed through the shunt field F as follows:—from positive main through wire 61, contact 55', blade 57, contact 54', wires 69, 70, and field winding F to the negative main. The accelerating magnet winding is also connected across the brushes of the motor armature through the following circuit—brush 64, wire 63, contact 53', blade 57, contact 54', wire 69, accelerating magnet H, wire 71, contact 72, wire 73, contact 54, blade 56, contact 55 and wire 66 to the brush 65. 130

It will thus be seen that when the switch is closed, as stated, the motor field will be excited; and a current also passes through the armature but with the resistance R and winding G in series. The accelerating magnet H which is constructed to operate its armatures $75, 76, 77, 78$, successively in a well-known manner as the current through the magnet increases, will not at first operate, owing to the low potential across the armature, but as the speed of the motor increases and the counter-electro-motive-force rises, the accelerating switches are operated successively to gradually cut out the resistance R and winding G . The motor M is connected to the worm shaft 15 in any suitable manner.

The operation of the elevator controlling devices will now be apparent. In Fig. 1 the parts are shown in their normal position of rest with the brake applied. If now the shipper sheave is moved, for example, to the left, the cam 31 will engage and operate the lever 28 to release the brake as before explained. At the same time the switch arms $56, 57$ engage the coöperating switch contact clips and establish a circuit through the motor M which is gradually brought up to speed, and operates through the worm shaft 15 and hoisting shaft 17 to lift or lower the elevator car. When it is desired to stop the elevator car, the shipper sheave is moved back to its central position, which opens the motor circuit and again applies the brake. If the shipper sheave is not operated manually before the car reaches its limit of movement, it will be operated automatically by the traveling nut 47 of the stop motion device, which will engage one of the stops 45 and 46 , depending on the direction of travel of the car, and operate as before pointed out. If it is desired to move the elevator car in the opposite direction, the shipper sheave is moved in the reverse direction to close the opposite set of switches. This will send a current through the motor armature in the opposite direction and cause a reversal of the motor. The circuit through the armature is now as follows:—through wire 61 , contact 79 , blade 57 , contact 81 , wire 66 , brush 65 , motor armature, brush 64 , wire 63 , contact 82 , blade 56 , contact 83 , wire 67 , resistance R , wire 68 , coil G to the negative main. It will thus be seen that the current through the armature is reversed but is in the same direction through the series field winding G . The direction of the current through the shunt field F also remains unchanged being as follows: from the positive main through wire 61 , contact 79 , blade 57 , contact 80 , wire 84 , contact $54'$, wires $69, 70$ and field winding F to the negative main.

In Fig. 4 is shown a somewhat modified arrangement of switch contacts and switch lever. The lever 85 is pivoted at 86 and com-

prises two switch blades $56, 57$ insulated from each other as in Fig. 3. When moved to the left the blade 56 will bridge the contacts $53, 54, 55$, and the blade 57 will bridge the contacts $53', 54', 55'$ the same as in Fig. 3. When the lever is moved in the opposite direction, corresponding contacts will be bridged. It will also be observed that the electrical connections between the various contacts in Fig. 4 are identical with those in Fig. 3. Figs. 5 and 6 show a modification in which the contacts are arranged in parallel rows. The blades 56 and 57 are here pivoted at one end to the base which carries the contacts, and as the blades are moved together in either direction, they will engage the same contacts as in Figs. 3 and 4.

I do not wish to be limited to the structural features, and arrangements of parts disclosed, as various modifications might obviously be made therein by those skilled in the art without departing from the spirit of my invention, or changing its scope as defined in the appended claims.

What I claim as new and desire to secure by Letters Patent of the United States is:—

1. In an elevator system, the combination with a hoisting drum, of a motor, a shipper sheave, means operated by the shipper sheave for controlling the hoisting drum, and means connected to the shipper sheave and operated by gravity for holding the shipper sheave in its operated position in either direction.

2. In an elevator system, the combination with a hoisting drum, of operating means therefor, a shipper sheave for controlling the operating means, and means carried by the shipper sheave for yieldingly holding it in its operated position, and means for limiting the movement of said sheave in either direction.

3. In an elevator, the combination with a shipper sheave, of operating means therefor, brake apparatus controlled by said sheave and means movable with the sheave for holding it yieldingly in its operated position with the brake released.

4. In an elevator, the combination of a shipper sheave operable in either direction, a brake controlled by said sheave, and a gravity operated device carried thereby for holding the sheave yieldingly in its operated position in either direction with the brake released.

5. In an elevator, the combination with a shipper sheave movable from a central position in either direction about its axis, of stops carried by the sheave, fixed stops in the path of movement of the first-named stops, to limit the movement of the sheave in either direction, and a weight carried by the sheave and movable into position to hold the sheave yieldingly at its limit of movement in either direction.

6. In an elevator system, the combination with a hoisting drum and an electric motor therefor, of a shipper sheave, fixed contacts in the motor circuit, switch blades carried by the sheave and movable therewith into engagement with the fixed contacts, and a weight carried by the sheave and movable therewith into position to hold the switch blades yieldingly in engagement with the fixed contacts.
7. In an elevator, the combination with a hoisting drum, of a brake therefor, a stop motion device comprising a traveling nut, and means carried by the nut for positively operating the brake.
8. In an elevator, the combination with a hoisting drum, of a brake therefor, a rotatable screw-threaded shaft, stops carried by the shaft, a traveling member on the shaft, and positive brake-applying connections between said member and the brake.
9. The combination with a screw-threaded shaft, of a traveling nut thereon, a stop for the nut, an electric switch comprising a stationary member and a member rotatable about the axis of said shaft, and a sliding connection between the nut and said rotatable member.
10. In an elevator, the combination with a hoisting drum, of a brake therefor, operating means for the brake, a shipper sheave, a screw-threaded shaft, a traveling nut on the shaft, stops therefor, means carried by the traveling nut for controlling the brake, and means for preventing rotation of the traveling nut independently of the sheave.
11. In an elevator, the combination with a hoisting drum, of a brake therefor, a rotatable screw-threaded shaft, a traveling nut on the shaft, a traveling nut on the shaft, stops for the nut carried by the shaft, a shipper sheave surrounding the shaft, a sliding connection between the shipper sheave and traveling nut preventing independent rotative movement between the sheave and nut, and means carried by the nut for actuating the brake-operating means when the shipper sheave is rotated.
12. In an elevator, the combination with a hoisting drum, of a brake therefor, a rotatable screw-threaded shaft, a traveling nut on the shaft, an arm extending from the nut, a lever in engagement with the arm, and operative connections between the lever and brake.
13. The combination with a direct current electric motor having a shunt field winding, of a source of current for the motor, a winding in series with the motor armature, a starting resistance in series with the armature and series winding, an accelerating magnet controlling the starting resistance and series winding, two series of contacts, the positive main having connections with
- one contact of each series and the negative main having connections through the series winding and starting resistance with another contact of each series, conductors extending from the armature brushes and having connections with another contact of each series, another contact in each series electrically connected, a connection between said last-named contacts and one terminal of the shunt field winding, a direct connection between the other terminal of the shunt field winding and one of the mains, another contact in each series, and electrical connection between said last-named contacts and between said contacts and one terminal of the accelerating magnet, a direct connection between the other terminal of the accelerating magnet and the shunt field contacts, contact bridging members insulated from each other and movable into one position in which one of the members bridges a positive main contact, a shunt field contact and an armature brush contact, and the other member bridges a negative main contact, an accelerating magnet contact and the other armature brush contact, said contact bridging members being movable into another position in which said first member bridges another positive main contact, another shunt field contact, and a contact connected to the other armature brush, and the other member bridges another negative main contact, another accelerating magnet contact and the other armature brush contact.
14. In an elevator system, the combination with a hoisting drum, of a brake therefor, operating means for the brake, a direct current motor, a shipper sheave mounted for rotation in either direction, contact blades carried by the sheave and extending outwardly therefrom, fixed contacts in the motor circuit with which one of the contact blades engages when the sheave is rotated in one direction to close the circuit through the motor in one direction, and fixed contacts in the motor circuit with which the other contact blade engages when the sheave is rotated in the reverse direction to close a circuit through the motor in a reverse direction, and means carried by the sheave and in engagement with the brake-operating means for applying the brake when the sheave is in its intermediate position, said means being movable with the sheave in either direction out of engagement with the brake-operating means.

In testimony whereof, I have signed my name to this specification in the presence of two subscribing witnesses.

WILLIAM H. HULTGREN.
